United States Patent Office

Des. 220,904
Patented June 15, 1971

220,904

STORE FRONT

Stanley A. Jacobs and Marjorie L. Jacobs, New Haven,
Conn., assignors to The Thin Man, Inc., New Haven, Conn.

Filed Nov. 12, 1969, Ser. No. 20,043

Term of patent 14 years

Int. Cl. D25—01

U.S. Cl. D13—1

Fig. 1.

Fig. 2.

Fig. 4.

Fig. 3.

Fig. 5.

FIG. 1 is a front elevation of a store front embodying our invention;

FIG. 2 is a plan view of the store front of FIG. 1;

FIG. 3 is a side elevation of the store front of FIG. 1 with the vertical wall omitted for convenience of illustration.

FIG. 4 is a view seen in the plane of lines 4—4 of FIG. 1;

FIG. 5 is a view seen in the plane of lines 5—5 of FIG. 1;

FIG. 6 is a view in perspective of another store front embodying the invention; and

FIG. 7 is a view seen in the plane of line 7—7 of FIG. 6.

We claim:

The ornamental design for a store front, as shown and described herein.
